UNITED STATES PATENT OFFICE.

GEORGE W. SHUGERS, OF LOS ANGELES, CALIFORNIA.

BLADE HOLDER.

Application filed February 14, 1920. Serial No. 358,682.

To all whom it may concern:

Be it known that I, GEORGE W. SHUGERS, a citizen of the United States, residing at 409 South St. Andrews Place, in the city 5 of Los Angeles, county of Los Angeles and State of California, have invented a new and useful Blade Holder, of which the following is a specification.

This invention relates to means for holding the detachable blade of safety razors for the purpose of sharpening the same and is also adapted to hold such blade for the purpose of shaving with the same.

An object of the invention is to provide 15 a very cheap, simple, convenient and efficient blade holder of this character adapted to allow the blade to be quickly and easily inserted and clamped in place and held firmly during the operation of either 20 sharpening the blade or shaving with the same, and adapted to readily release the blade when that is desirable. My invention comprises a blade holder having a main body and a clamping limb cooperat- 25 ing therewith, said body being of greater width than its clamping limb, thus allowing easy access to the blade and one edge thereof, and protecting the other edge, and providing a very firm and resilient clamp- 30 ing means.

The invention is adapted to be made mainly from a single sheet metal stamping, and is provided with a handle and with a latch. It comprises a body provided at one 35 end with a clamping limb which is bent over into clamping position relative to the body and is adapted to allow a blade to be inserted between it and said body. Latch means are provided to latch the limb to the 40 body in blade clamping position.

In order to facilitate the turning of the holder on a strop during the operation of stropping the blade, a rounded back is applied to the body and is preferably made as 45 an extension of the body stamping extending opposite to the clamping edge of such body and bent over to form the rounded back.

Said stamping is also formed with a 50 shank to which a handle may be attached and the clamping limb is of spring metal bent to hold one end away from the body to form an open space between the body and limb into which the blade may be inserted; 55 and the latch may be pivoted to the body and provided with a keeper to extend over

the end of the limb to hold said limb and body in blade clamping position.

The invention may be constructed without a solid rounded back and I shall illustrate it as constructed with a tubular back, 60 the ends of which are adapted to be closed by a plug or cap if it is desired to construct the device with an apparently solid back.

Other objects, advantages and features of invention may appear from the accompanying drawings, the subjoined detail description and the appended claims.

The accompanying drawing illustrates the 70 invention.

Figure 1 is a perspective view of the blade holder with blade clamped in position.

Fig. 2 is a perspective view of the holder shown in Fig. 1 with the parts in position 75 to receive the blade which is shown partly inserted into the clamp.

Fig. 3 is an end elevation of the completed device shown in Figs. 1 and 2.

Fig. 4 is an end elevation of the device 80 without the handle as viewed from the handle end.

Fig. 5 is a plan of the sheet metal stamping adapted to form the holder apart from the latch.

Fig. 6 is a perspective of the latch detached.

Fig. 7 is a plan of a stamping for forming the latch.

The body 1 is of a predetermined width 90 and is of a length somewhat greater than the length of the blade to be clamped. The clamping limb 2 is shown as formed of an extension from one end of the main body and a narrower width than said main body; 95 said limb being bent over at 3 with a short resilient bend and the limb being normally separated from the main body by the resiliency of the bend at the body, and the spring of the limb. Said body and limb are adapted to be held by a latch 5 pivoted to the body by a rivet 6 and having a keeper 7 adapted to extend over the tip of the limb when the limb is brought into blade clamping position.

The rounded back 8 may be formed in any suitable way, but for cheapness and convenience of manufacture the stamping is provided with an upward extension 9 opposite to the clamping edge 10 of the holder. 110 Said extension projects beyond the clamping edge 10 of the main body and is sepa-

rated therefrom by a slit 11, thus allowing the extension to be bent away from the body at 12 and thence around into the form to bring its outer edge 13 against the body 1.

Said body is provided with a shank 14 to which a suitable handle 15 is secured in any well known way.

The latch is formed of a sheet metal stamping having an eye 16 on the same edge with the keeper 7. Said keeper 7 is bent away from the binding surface of the latch so as to accommodate the tip of the limb when said limb is brought into clamping position. The latch preferably extends rearwardly from the pivot to a point beyond the back of the main body and is there bent over to form a loop 17 loosely embracing the back of the main body and accommodating the pivotal movement of the latch to allow the keeper to be applied to and withdrawn from the end of the limb by pressure upon the loop in one or the other direction.

In practical operation the user will hold the handle 15 in his hand in the same manner as with a razor of the pivoted blade type and will allow the limb to spring away from the main body so as to form an opening into which the blade 18 to be sharpened or used may be inserted. Then by pressure upon the outwardly bent end of the limb, he will bring the tip of the limb into position to be caught by the keeper and will then operate the latch with his forefinger tip to bring the keeper over the tip of the limb, thus clamping the blade tightly. The blade will usually be adjusted to project about a quarter of an inch more or less from the clamping

edges of the body and limb, and when so clamped, the operation of sharpening the 40 blade or of shaving with the blade can be easily performed.

I claim.

1. A blade holder comprising a stamping of sheet metal provided with a limb and a body wider than said limb; said sheet metal limb and body being bent to form a clamp for holding the blade; latch means to hold the body and limb in blade clamping position comprising a stamping pivoted to said body and having a keeper to engage said limb, said latch being bent to form a loop loosely embracing the back of the body and a rounded back formed by an extension of said body.

2. The blade holder stamping set forth comprising a body portion, a limb portion extending from one end of the body portion, a back extension extending beyond the body portion at the edge opposite the edge adjacent the limb; said extension being adapted to be bent to form a tubular back and said limb being adapted to be bent to form a clamp member to cooperate with the body portion; and a latch bent to form a keeper adapted to accommodate the tip of said limb when in clamping position, and bent to form a loop loosely embracing the body portion.

In testimony whereof, I have hereunto set my hand at Los Angeles, California, this 6th day of February, 1920.

GEORGE W. SHUGERS.
